UNITED STATES PATENT OFFICE.

JOHN H. STOCKHOLDER, OF NEW ORLEANS, LOUISIANA.

BOILER ATTACHMENT.

Application filed March 23, 1926. Serial No. 96,759.

The invention relates to boiler attachments, and has for its object to provide a device of this character whereby, when the water level within the boiler drops below a danger level, live steam from the boiler will be allowed to escape from the boiler and be discharged into the fire box below the boiler thereby extinguishing the fire, and obviating danger of explosion or damage to the boiler.

A further object is to place a fusible member in a bushing, which bushing is threaded into a branch of a **T** fitting and to proportion the opposite branch of the **T** fitting whereby the bushing may be removed therefrom, thereby allowing the fusible plug and the bushing to be easily removed and replaced as desired and to provide the branch of the **T** opposite the bushing carrying branch with a removable plug, whereby access may be had to the bushing.

A further object is to provide a valve interposed between the fusible plug and the boiler, which may be closed when placing a new fuse therein after a fusing operation.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:—

Figure 1 is a side elevation of a conventional form of boiler, showing the same partially in vertical longitudinal section and the device applied thereto.

Figure 2 is a vertical longitudinal sectional view through the **T**.

Referring to the drawing, the numeral 1 designates a conventional form of boiler and 2 a fire box beneath the same. In boilers as at present constructed fuse plugs are used, however when the regulation fuse plug gives way the boiler has to cool off and a new plug is then inserted from the inside of the boiler, consequently the boiler is out of commission for at least twenty four hours, and to obviate the above difficulty the present device is primarily designed. Extending down-

wardly into the boiler, through the upper side thereof at 3 is a pipe 4, which pipe extends below the water level 5 within the boiler to a predetermined danger line 6, and when the water drops below the danger line 6 the live steam within the boiler is allowed to pass through the pipe 4, however at other times the water forms a seal for the lower end of the pipe 4 and prevents the passage of steam into the same. Pipe 4 above the boiler is provided with a conventional form of valve 7 which is normally open, and secured to the valve 7 is a **T** 8 having its lower branch 9 provided with a removable bushing 10, and in which bushing is disposed a fusible plug 11, which plug will fuse when the live steam engages the same, thereby allowing the steam to pass through the bushing 10 to the chamber 12 of the **T** and thence through the pipe 13 which is connected to the branch 14 of the **T**, and which pipe extends downwardly and terminates in a horizontally disposed portion 15 which has its discharge end disposed within the fire box 2. It will be seen that the live steam from the boiler will be discharged into the fire box, consequently the fire will be extinguished, all of which is a relatively quick operation. The fireman can then remove the plug 16 from the upper branch 17 of the **T** and remove the bushing 10 from which the fuse plug 11 has been fused from its position in the branch 9 and easily and quickly replace the same with another bushing having a fuse plug therein, and which operation may be easily accomplished with a conventional form of socket wrench.

From the above it will be seen that a steam exhausting apparatus is provided for boilers whereby danger of explosion of the boiler is obviated, the fusible plug can be quickly replaced with another plug and at the same time the fire is extinguished, all of which operation takes place within a relatively short time, thereby obviating the necessity of placing the boiler out of commission and allowing the same to cool, which is the present practice.

The invention having been set forth what is claimed as new and useful is:—

The combination with a pipe extending into a boiler to a position below the water

level thereof, a fire box, said pipe having one of its ends extending into the fire box, a valve carried by said pipe adjacent the boiler, a **T** fitting carried by said valve and 5 pipe and having oppositely disposed branches, a bushing threaded into one of said branches and removable through the

other branch, a fusible plug carried by said bushing and a removable plug carried by the branch of the **T** fitting opposite the 10 bushing-carrying branch.

In testimony whereof I hereunto affix my signature.

JOHN H. STOCKHOLDER.
